UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL-LIFT-ALIGNING DEVICE.

Application filed April 20, 1919. Serial No. 293,671.

To all whom it may concern:

Be it known that I, ERASTUS E. WINKLEY, a citizen of the United States, residing at Lynn, in the county of Essex and State of Massachusetts, have invented certain new and useful Improvements in Heel-Lift-Aligning Devices; and I do hereby declare the following to be a full, clear, and exact description of the invention, such as will 10 enable others skilled in the art to which it appertains to make and use the same.

This invention relates to devices for relatively positioning and aligning the component lifts of loosely assembled heels.

15 A device for performing a similar operation is illustrated and described in a co-pending application, Serial No. 283,693, filed March 20, 1919, by the present applicant, in which the heels are placed so that 20 the lifts rest in loose order in a form consisting of a plurality of movable aligning jaws which operate in conjunction with each other to effect the alignment of the heel lifts in two stages. Four jaws are provided 25 to engage the sides of the heel at different points while a fifth jaw is adapted to engage the rounded rear end thereof. These jaws are moved into an initial position to preliminarily position the lifts while they 30 are assembled in loose order and subsequently, the jaws are shifted into final aligning position.

The primary object of the present invention is to produce an efficient and reliable 35 device of the general character above referred to, which is of simple and inexpensive construction, and which is provided with means for acting independently upon each of the component lifts of a loosely assembled 40 heel to effect their alignment.

To this end provision is made for receiving a heel pile of loosely assembled lifts, in a heel form having a surface adapted to engage the breast edges of the lifts, and for 45 forcing the lifts in a direction to align their breast edges against said surface by means of a movable member having a plurality of lift engaging members which are laterally movable independently of each other. The 50 heel form is preferably arranged to receive the heel pile between end supporting pressure-applying members and lateral edge guides, with the breast of the heel resting upon a bed plate. The lifts are aligned

against the bed plate and with respect to 55 the lateral edge guides by means of a plurality of pointed resilient fingers, which are carried by the movable member that is adapted to be actuated to bring the pointed ends of the fingers into engagement with the 60 rounded rear edges of the individual lifts and to press the lifts towards the bed plate. Such lifts as are angularly disposed in the heel pile will be rotated about one corner by the pressure of their respective fingers until 65 properly positioned between the edge guides and squarely alined against the bed plate. Certain other features will be hereinafter referred to in the description and pointed 70 out in the appended claims.

The preferred embodiment of the invention is illustrated in the accompanying drawings, in which Figure 1 is a plan view of the device in its operative position; Fig. 2 is a view in side elevation thereof, showing the inoperative position of the movable aligning instrumentalities; Fig. 3 is a view in end elevation of the device, looking from the right in Fig. 1; Fig. 4 is a view similar to Fig. 2, showing the aligning instrumentalities in operative position; and Fig. 5 is a diagrammatic view illustrating the manner of aligning the heel lifts.

In the drawings a bed plate 2 has an upwardly projecting portion 4 which supports 85 a fixed upright pressure plate 6. Resting upon the bed plate opposite the plate 6 is a cooperating pressure block 8, which is fixed to one end of an operating rod 10, that is mounted to slide in a bearing 12 to actuate 90 the block 8 toward and away from the plate 6. Secured to the bed plate at each side of the plate 6 and the block 8 are guide bars 14. The plate 6, the block 8, the guide bars 14 and the bed plate form respectively the 95 four sides and the bottom of a heel form which is adapted to receive a loosely assembled heel 16. The guide bars 14 serve as lateral edge guides for the lifts and are beveled as shown in Figs. 1 and 3 to facilitate the insertion of the heel pile into the form, and they also diverge from the plate 6 to accommodate the pitch of the heel pile. The guide bars, as shown in Fig. 1, are secured to the bed plate with provision for 100 relative adjustment to permit them to be adapted for use in connection with heel piles of varying sizes and styles.

The means for insuring proper alinement of the lifts comprises a vertically movable arm 18 carrying a plurality of bent resilient fingers 20, the pointed ends of which are 5 adapted to engage the rear rounded edges of the lifts. The arm 18 is provided with a handle 22 and is pivoted at 24 between ears 26 of a member 27 rising from the bed plate. The fingers 20, of which there is one for each 10 lift in the heel that is to be operated upon, are arranged in a row with their upper ends clamped between a pair of plates 28 by means of bolts 30 which serve also to secure the clamping plates 28 to the arm 18. The 15 fingers are adjusted to engage their respective lifts when the arm 18 is in operative position, as indicated in Fig. 4, and they are spaced apart so as to be free to yield laterally independently of each other in 20 order that they may participate in the rotating movement of any angularly displaced lifts and offer no resistance thereto. Each finger 20 is bent or bowed laterally in the plane of the lift which it is arranged to engage, as illustrated clearly in Fig. 3, in order 25 that it may yield vertically when put under pressure, thereby insuring a substantially even application of pressure to each lift.

Normally the arm 18 occupies an inoperative position against a stop 32 forming a part of the member 27, as indicated in Fig. 2, but it is adapted to be swung downwardly by means of the handle 22, into the position shown in Fig. 4, so as to bring the lower 30 pointed ends of the fingers 20 into engagement with the rear edges of the lifts, and to press the lifts downwardly between the beveled edge guides until their breast edges rest squarely upon the bed plate. As pressure is applied to the arm 18, the ability of 35 the fingers 20 to yield in the direction of their movement will insure that each of the component lifts of the heel will be independently engaged and pressed toward the bed plate. The fingers 20, by reason of their 40 ability to yield laterally, in the planes of the lifts, will also cause such lifts as may be angularly disposed in the heel pile to be severally rotated about one corner until the 45 breast edges thereof are properly alined against the bed plate. In this way all of the lifts are acted upon in a manner to insure their proper alinement. The pointed 50 ends of the fingers prevent them from slipping sidewise from the rounded edges of the lifts as the lifts are being brought into alinement. The pointed lift engaging ends 55 of the fingers normally lie in the central vertical longitudinal plane of the heel form, but during the process of aligning the lifts, the fingers are permitted to yield laterally as required by the change of angular position of the lifts.

The manner in which an angularly disposed lift is rotated about one of its corners

in order to bring its breast edge squarely against the bed plate is illustrated by Fig. 5. The full lines in this figure indicate an aligning finger as it appears while engaging an angularly disposed lift, before it has imparted any rotating movement thereto. The dotted lines represent the positions of the lift and the finger after the lift has been rotated into position. It will be apparent 70 that there will be no frictional rubbing of the aligning finger over the rear edge of the lift engaged thereby, while the lift is being rotated, as would be the case if the aligning member were movable only in a single plane. Consequently instead of offering any resistance to the angular movement 75 of the lifts, the resilient fingers participate in said movement and a positive and perfect alinement is assured.

When the lifts have all been brought into proper alinement, pressure is applied to the block 8 through the rod 10 by any suitable means, not shown in the drawing, so as to hold the lifts firmly while they are being 80 permanently secured together by the driving of a nail through the pile from the top lift to the base lift. As shown in Fig. 2, the plate 6 carries a nail throat 34, which is mounted in the member 27 between the ears 26 and parallel to the bed plate, through 85 which nails may be driven into the heel pile by a nail driver 36 which may be operated by any usual or suitable means.

While the drawings illustrate the invention as embodied in a device adapted to receive a stack of lifts in upright position upon a horizontal support, it is to be understood that the invention is not limited to such an arrangement, as it may equally well be embodied in a device adapted to receive 100 and operate upon the lifts while they are in a horizontal or any other position. The details of construction may also be variously modified without departing from the spirit 105 of the invention as defined in the following 110 claims.

Having thus described the invention, what is claimed as new is:—

1. A heel lift aligning device having, in combination, a form adapted to receive a 115 loosely assembled heel, and means capable of lateral movement for acting independently upon each of the component lifts of the heel to effect their alinement.

2. A heel lift aligning device having, in 120 combination, a form adapted to receive a loosely assembled heel, and means capable of engaging the edge of each of the component lifts of the heel and yielding laterally to permit edgewise angular movement of 125 the lifts for insuring the individual positioning thereof.

3. A heel lift aligning device having, in combination, a form adapted to receive a 130 loosely assembled heel, and means comprising

- ing a plurality of members capable of independent relative movement in all directions in the planes of the lifts and arranged to severally engage the component lifts of the heel to effect their alinement.
4. A heel lift aligning device having, in combination, a support for the breast edges of the component lifts of a loosely assembled heel, means for maintaining said lifts in stacked relation, an arm pivotally connected with said support and movable toward and away from the rear of the heel, and movable means carried by said arm comprising a plurality of members adapted to severally and independently engage the rounded rear edges of the respective lifts of the heel for effecting the alinement of the breast edges thereof against said support.
5. A heel lift aligning device having, in combination, a support for the breast edges of the component lifts of a loosely assembled heel, means for maintaining said lifts in stacked relation, and movable means comprising a plurality of members adapted to severally and independently engage the rounded rear edges of the respective lifts of the heel for effecting the alinement of the breast edges thereof against said support, said members being independently adapted to yield both in the direction of their movement and laterally thereof in the planes of the lifts.
6. A heel lift aligning device having, in combination, a form adapted to receive a loosely assembled heel, and means comprising a plurality of positioning members adapted for independent lateral movement and arranged to engage the rounded rear edges of the lifts for positioning the component lifts of the heel with their breast edges in alinement.
7. A heel lift aligning device having, in combination, a form adapted to receive a loosely assembled heel, and means comprising a plurality of fingers of resilient material arranged to engage the rounded rear edges of the lifts for positioning the component lifts of the heel with their breast edges in alinement.
8. A heel lift aligning device having, in combination, a support for the breast edges of the component lifts of a loosely assembled heel, means for maintaining said lifts in stacked relation, and movable means comprising a plurality of fingers of resilient material adapted to engage the rounded rear edges of the lifts for aligning the breast edges of the lifts against said support.
9. A heel lift aligning device having, in combination, a support for the breast edges of the component lifts of a loosely assembled heel, means for supporting the end lifts, edge guides for positioning the lifts laterally, and means comprising a plurality of fingers of resilient material adapted to engage the rounded rear edges of the lifts for aligning the breast edges of the lifts against said support.
10. A heel lift aligning device having, in combination, a support for the breast edges of the component lifts of a loosely assembled heel, means for supporting the end lifts, an arm pivotally connected with said support and movable toward and away from the rear of the heel, and a plurality of resilient fingers carried by the arm and arranged to be brought into engagement with the rear edges of the lifts to align them against said support.
11. A heel lift aligning device having, in combination, a support for the breast edges of the component lifts of a loosely assembled heel, means for supporting the end lifts, movable means comprising a plurality of resilient fingers adapted to engage the rounded rear edges of the lifts and to yield in all directions in the planes of the lifts for aligning the breast edges of the lifts against said support, and means for securing the lifts together.
12. A heel lift aligning device having, in combination, a support for the breast edges of the component lifts of a loosely assembled heel, means for supporting the end lifts, and means comprising a plurality of fingers adapted to engage the rounded rear edges of the lifts and to yield laterally under pressure tending to move the fingers toward said support for forcing the breast edges of the lifts against said support.
13. A heel lift aligning device having, in combination, a support for the breast edges of the component lifts of a loosely assembled heel, means for supporting the end lifts, and means comprising a plurality of fingers adapted to engage the rounded rear edges of the lifts for forcing the breast edges of the lifts against said support, each finger being bent laterally substantially in the plane of the lift engaged thereby to permit the finger to yield under pressure.
14. A heel lift aligning device having, in combination, means against which the breast edge of the lift is to be positioned, and movable means comprising a resilient finger for engaging the rounded rear edge of the lift and forcing its breast edge into engagement with said first means, said finger being adapted to yield both in the direction of its movement and laterally thereof in the plane of the lift.
15. A heel lift aligning device having, in combination, a support for the breast edges of the component lifts of a loosely assembled heel, means for maintaining the lifts in stacked relation, means for engaging and guiding the lateral edges of the lifts, and means comprising a plurality of members adapted to yield laterally in the planes of

- the lifts, said members being severally adapted to engage the rear edges of the respective lifts and serving in conjunction with said other means to laterally aline the 5 component lifts of the heel and to force the breast edges thereof into engagement with said breast support.
16. A heel lift aligning device having, in combination, means adapted to receive a 10 loosely assembled heel, means comprising a plurality of members constructed to penetrate the rounded rear edges of the lifts, and means for pressing said members against the lifts.
17. A heel lift aligning device having, in combination, means adapted to receive a loosely assembled heel, including a breast gage, and means for seating irregularly placed lifts against said breast gage comprising flexible metallic fingers sufficient in 15 number to engage each lift and each pro- vided with a sharpened end to enter the lifts at their rounded rear edges.
18. A heel lift aligning device having, in combination, means adapted to receive a 20 loosely assembled heel, including a breast gage, and means for seating irregularly placed lifts against said breast gage comprising means for positively engaging said lifts and movable laterally with the lifts as 25 they turn to proper position.
19. A heel lift aligning device having, in combination, a form in which a loosely assembled heel is placed with the breast edges thereof directed toward a plate forming a 30 breast gage, a device at the rear edges of the lifts for seating irregularly placed lifts against said plate comprising a series of 35 pointed fingers for engaging the lifts, and a lever movable toward and from the heel on 40 which said fingers are supported.

ERASTUS E. WINKLEY.
